(57) **CLAIM**

The ornamental design for a drawing tool, as shown and described.

DESCRIPTION

FIG. 1 is a top-front-left perspective view of a drawing tool showing my new design;

FIG. 2 is a top-front-right perspective view thereof;

FIG. 3 is a top-rear-left perspective view thereof;

FIG. 4 is a top-rear-right perspective view thereof;

FIG. 5 is a bottom-front-right perspective view thereof;

FIG. 6 is a bottom-rear-left perspective view thereof;

FIG. 7 is a front elevated view thereof;

FIG. 8 is a rear elevated view thereof;

FIG. 9 is a top plan view thereof;

FIG. 10 is a bottom plan view thereof;

FIG. 11 is a right side elevation view thereof; and,

FIG. 12 is a left side elevation view thereof.

The broken lines showing of orifices in FIGS. 1-10, the broken lines showing of a spring mechanism in FIGS. 1-8 and 12, and the broken lines showing of hinges in FIGS. 1-12 are included for the purpose of showing environmental structure and form no part of the claimed design.
